Des. 1832

R. Wheeler and S. A. Bailey, of Utica N.Y.

Letters Patent No. 1832 dated Oct 18th 1868.

Design for a Parlor Stove.

The schedule referred to in these Letters Patent and making part of the same.

To all whom it may concern:

Be it known that we, Russell Wheeler and Stephen A. Bailey, of the City of Utica, in the County of Oneida, and State of New York, have invented a new and improved design for a coal stove; and we hereby declare that the following is a full and exact description thereof, reference being had to the accompanying drawings.

The nature of our invention consists in a new design for a coal stove, as represented in the accompanying drawings.

To enable others skilled in the art to make and use our invention, we will proceed to describe its design and construction.

The top is of cast iron, and its ornaments are designated by the letter A. The door designated by the letter B, is of cast iron. The lower section of the stove is of cast iron, and its mouldings are designated respectively by the letters C, and D, all of which are represented on the accompanying drawings.

What we claim as our invention and design, and desire to secure by Letters Patent, is, the design for a coal stove as above described and represented.
